UNITED STATES PATENT OFFICE

ROGER K. LEE, OF DETROIT, MICHIGAN

SIGNALING DEVICE

Application filed October 23, 1929. Serial No. 401,651.

This invention relates to signaling devices.

The main objects of this invention are to provide an improved signaling apparatus which has a plurality of musical notes; to 5 provide a signaling apparatus in which a plurality of reeds of different tones are actuated in succession from a common air source; to provide a multi-toned signaling horn in which the different notes may be produced 10 in succession and thereafter in unison; to provide an improved bellows and housing for creating the air flow to operate the reeds; and to provide an improved controlling means by the use of which the length of the musical 15 notes and their spaced relation from one another may be fixed as desired.

An illustrative embodiment of this invention is shown in the accompanying drawings, in which

20 Fig. 1 is a vertical medial longitudinal sectional view of my improved signaling device mounted on a supporting base.

Fig. 2 is a sectional view taken on the line 2—2 of Fig. 1 looking in the direction indicated by the arrows.

Fig. 3 is a fragmentary sectional view taken on the line 3—3 of Fig. 1 looking in the direction indicated by the arrows.

In the construction shown in the drawings 30 a vertically extending disc-shaped base plate 5 is shown provided with a horizontally and rearwardly extending attaching foot 6 which is adapted to be secured by screws or bolts 7 to a convenient and accessible part of the motor vehicle, or other place where the signaling device is desired.

The base member 5 has a tubular casing or cylinder 8 preferably of sheet metal, securely attached thereto, as by welding an outwardly 40 turned flange 9 of the casing 8 to the marginal edge of the base plate 5, said base plate serving to close one end of the tubular casing 8.

The opposite end of the cylinder 8 is provided with a disc-shaped head 10 which has a marginal flange 11 for surrounding and snugly receiving the end of the cylinder. The flange 11 may be soldered, welded or otherwise suitably secured to the end of the cylinder.

The head 10 is provided with an opening 12 which has an inwardly opening valve 13 yieldably held thereagainst by a spring arm 14, one end of which is attached to said valve and the other end of which is rigidly secured 55 to the casing 8 by suitable means such as a rivet 15.

The base plate 5 has a plurality of equi-distantly spaced openings therethrough, which are threaded to receive a like number of 60 tubular sleeves 16 which have one end threaded thereinto and the other ends of which support diverging horn or amplifying tubes 17. The tubes 17 are each provided with a musical sound making unit which includes a reed 65 19. Any desired number of these musical note making units with amplifying horns of appropriate length may be provided, the construction of each being substantially identical with the others, with the exception of the 70 tones emitted therefrom, the object being to provide a pleasing combination of tones which will be in chord with each other.

Means are provided for passing air under pressure through each of these sound making 75 units, individually or in unison, and comprise a bellows 20 preferably of molded live rubber, the bellows having one end with a wall molded integrally therewith and the other end open. The closed end of the bellows is mounted on a disc-shaped plate 21 of sheet metal, which has ears or lugs 22 turned inwardly at suitably spaced intervals, for embracing the adjacent fold or convolution of the bellows. The folds of the bellows, both inwardly and outwardly, are each provided with wire rings 23 which serve to prevent the bellows from collapsing during use.

The plate 21 and closed end of the bellows 20 are held securely against the base plate 5 90 by an axially extending stud 24 formed on a body guide member 25 and into which is threaded a screw 26 bearing against a washer 27. The arrangement is such that the screw 27 clamps the parts together between the washer 95 27 and the guide member 25, which is of considerably larger size than the stud 24. The open end of the bellows 20 is closed by a piston head 28 which is axially slid able within the casing 8 and which has inturned lugs or fin- 100

gers 29 which partially surround and embrace the adjacent last convolution of the bellows and wire ring contained therein.

The plate member 21 and closed end of the bellows resting thereagainst are provided with registering apertures, the marginal edges of which are secured together by a grommet 30. The base 5 is also provided with an aperture 31 therein which is in registry with the opening through the grommet 30 so that the interior of the bellows is in communication with the atmosphere at all times.

Means are provided for elongating the bellows 20 against the action of a compression spring 32 which is interposed between the piston head 28 and cylinder head 10, and comprise an axially extending piston rod 33, one end of which is secured to the piston 28 by a clip 34. The other end of the rod extends through a pliable gasket bushing 35 mounted in the cylinder head 10, and the tip end thereof is provided with a handle in the form of a button 36 which may be conveniently grasped by a user for pulling the piston rod outwardly. The interior of the tubular casing 8, adjacent the cylinder head 10, is provided with a sleeve 37 against which the piston 28 will abut to limit its movement toward the valve 13, thereby preventing accidental damage to said valve.

The piston 28 is provided with a plurality of apertures 38 so that air displaced in the tubular casing 8 by manual movement of the bellows will pass through said apertures around the outside of the bellows, thence through the openings provided by the striking out of the tongues 22, and then through apertures 39 provided in a stepped portion of the plate 21, so that the air will pass down between the closed end of the bellows and the plate 21, and out through apertures 40 which are provided in the plate 21 in registry with the tubes 16 which support the note making units.

Means are provided for controlling the passage of air out through the different signal units and comprise valves 41 pivotally hinged at 42 on clips 43, which are riveted or otherwise suitably secured to the plate 21 on the inside of the bellows. A compression spring 44 is provided between the valve 41 and an arm 45 of the clip 43, for normally urging the valve 41 so as to press the end of the bellows therebeneath tightly against the discharge opening 40 provided in the plate 21.

The valves 41 have axially extending arms 46 which have raised portions 47 and 48 in position to be engaged by laterally extending lugs 49 integrally formed on a guide sleeve 50 by striking out and suitably bending a portion of said sleeve. The guide sleeve 50 is rigidly mounted on the piston 28 and is axially slidable on the guide member 25 so as

to support the entire unit centrally within the casing.

In the construction illustrated, the guide member 25 and co-operating sleeve 50 are of square cross section in shape and each of the four sides of the sleeve has a lug struck out therefrom, one for each valve arm of each of the four signaling units. Any suitable number, however, may be provided as desired.

In the operation of this signaling device, the handle 36 is grasped and drawn outwardly against the action of the spring 32, thereby displacing the air within the tubular casing 8 and causing it to pass forwardly around the outer side of the bellows 20 through the apertures 39 and down between the closed end of the bellows and the supporting plate 21. Movement of the piston 28 carries the guide sleeve 50 outwardly and causes the projecting lugs 49 to engage the raised portions 47 of the valve arms 46, thus swinging said arms against the action of their respective compression springs 44. Such movement of the valve arm raises the valve 41 from contact with the closed end of the bellows therebeneath, and permits the displaced air under pressure within the casing 8 to pass out through the openings 40 into the signal making units which communicate therewith.

The raised portions 47 are spaced at different longitudinal positions so that the valves are operated in succession, and by varying the length of the raised portion 47, the time interval may be varied so as to produce notes of various length as desired.

When the piston head 28 approaches its limit of movement all of the lugs 49 engage the raised portions 48 of the valve arms in unison, thereby opening all of the valves at once, thus producing a charded chimed blast from the signaling device.

Although but one specific embodiment of this invention has been herein shown and described, it will be understood that numerous details of the construction shown may be altered or omitted without departing from the spirit of this invention, as defined by the following claims.

I claim:

1. A signaling apparatus comprising an air motor, means for operating said motor, a signal device communicating with said air motor, a valve for controlling such communication, and means actuated by said motor operating means for operating said valve.

2. A signaling apparatus comprising an air motor, operating means for said motor, a plurality of signaling devices communicating with said motor and means operated by said motor operating means for controlling the operation of said signaling devices.

3. A signaling apparatus comprising a chamber, means for discharging air from said chamber, a signal device communicating with the discharge of said chamber, and means op-

erated by said discharging means for controlling the flow of air to said signal device.

4. A signaling apparatus comprising a chamber, means for discharging air from said chamber, a plurality of signaling devices communicating with the discharge of said chamber and means operated by said discharge means for passing the discharged air to said signaling devices in succession.

10 5. A signaling apparatus comprising a chamber, means for discharging air from said chamber, a plurality of signaling devices communicating with the discharge of said chamber and means operated by said discharge means for passing the discharged air to said signaling devices in succession, and thereafter in unison.

20 6. A signaling apparatus comprising a chamber having a plurality of discharge outlets, signaling devices communicating with said outlets, means for discharging air from said chamber through said outlets, valves for controlling said discharge outlets and means operated by said discharge means for operating said valves.

30 7. A signaling apparatus comprising a chamber having a plurality of discharge outlets, signaling devices communicating with said outlets, means for discharging air from said chamber through said outlets, valves for controlling said discharge outlets and means operated by said discharge means for operating said valves in succession.

35 8. A signaling apparatus comprising a chamber having a plurality of discharge outlets, signaling devices communicating with said outlets, means for discharging air from said chamber through said outlets, valves for controlling said discharge outlets and means operated by said discharge means for operating said valves in succession and thereafter in unison.

40 9. A signaling apparatus comprising a plurality of air operated signal devices, an air chamber communicating with said devices, valves which control the communication to said devices, a movable wall in said air chamber for discharging the air therefrom and cooperating means between said wall and valves for operating said valves when said wall is moved.

45 10. A signaling apparatus comprising a plurality of air operated signal devices, an air chamber communicating with said devices, valves which control the communication to said devices, a movable wall in said air chamber for discharging the air therefrom and cooperating means between said wall and valves for operating said valves in succession when said wall is moved.

50 11. A signaling apparatus comprising a plurality of air operated signal devices, an air chamber communicating with said devices, valves which control the communication to said devices, a movable wall in said

air chamber for discharging the air therefrom and cooperating means between said wall and valves for operating said valves in succession and thereafter in unison when said wall is moved.

70 12. A signaling apparatus comprising a chamber, an inwardly opening air valve for said chamber, a bellows within said chamber for displacing the air therefrom, a discharge outlet for said chamber, a signal device communicating with said outlet, a valve for controlling the communication between said chamber and signal device, means for moving said bellows to discharge air from said chamber, and means operated by the movement of said bellows for actuating said valve.

75 13. A signaling apparatus comprising a chamber, an inwardly opening air valve for said chamber, a bellows within said chamber for displacing the air therefrom, a discharge outlet for said chamber, a signal device communicating with said outlet, a valve for controlling the communication between said chamber and signal device, means for expanding said bellows, and means operated by the expansion of said bellows for opening said valve.

80 14. A signaling apparatus comprising a chamber, an inwardly opening air valve for said chamber, a bellows within said chamber for displacing the air therefrom, a plurality of discharge outlets, air operated signal devices communicating with said outlets, valves for controlling communication between said chamber and signal devices, means for expanding said bellows to discharge air from said chamber and means successively operated by the expanding movement of said bellows for opening said valves.

85 15. A signaling apparatus comprising a chamber, an inwardly opening air valve for said chamber, a bellows within said chamber for displacing the air therefrom, a discharge outlet for said chamber, a signal device communicating with said outlet, a valve for controlling the communication between said chamber and signal device, manually operable means for expanding said bellows, means operable by the movement of said bellows for actuating said valve, and automatic means for contracting said bellows.

90 16. A signaling apparatus comprising a chamber, an inwardly opening air valve for said chamber, a bellows within said chamber for displacing the air therefrom, a plurality of discharge outlets for said chamber, signal devices for said outlets, valves for controlling communication between said chamber and signal devices, manually operable means for expanding said bellows to discharge air from said chamber, means successively operated by the expanding movement of said bellows for opening said valves, and automatic means for contracting said bellows.

95 17. A signaling apparatus comprising a

supporting frame, a cylindrical chamber having one end mounted on said frame, an axially disposed guide mounted on said frame and extending within said chamber, a bellows within said chamber surrounding said guide, one end of said bellows being secured to said frame, a head on the other end of said bellows, a guide on said head axially slidably on and interfitting with said first mentioned guide, a manually operable axially slidable rod connected to said bellows head for expanding said bellows, automatic yielding means for contracting said bellows, an inwardly opening air valve for said chamber, a plurality of discharge outlets for said chamber, signal devices communicating with said outlets, valves for controlling the communication between said chamber and said signal devices and cooperating means between said bellows head guide and said valves for opening said valves in succession when said bellows is expanded.

18. A signaling apparatus comprising a supporting frame, a cylindrical chamber having one end mounted on said frame, an axially disposed guide mounted on said frame and extending within said chamber, a bellows within said chamber surrounding said guide, one end of said bellows being secured to said frame, a head on the other end of said bellows, a guide on said head axially slidably on and interfitting with said first mentioned guide, a manually operable axially slidable rod connected to said bellows head for expanding said bellows, automatic yielding means for contracting said bellows, an inwardly opening air valve for said chamber, a plurality of discharge outlets for said chamber, signal devices communicating with said outlets, valves for controlling the communication between said chamber and said signal devices, cooperating means between said bellows head guide and said valves for opening said valves in succession when said bellows is expanded, and thereafter opening all of said valves in unison.
